UNITED STATES PATENT OFFICE.

DAVID JAMES HURLEY, OF SALE, VICTORIA, AUSTRALIA.

DOOR CHECK AND CLOSER.

1,049,096.

Specification of Letters Patent. Patented Dec. 31, 1912.

Application filed June 17, 1912. Serial No. 704,143.

To all whom it may concern:

Be it known that I, DAVID JAMES HURLEY, a subject of the King of Great Britain and Ireland, &c., residing at Sale, in the 5 State of Victoria, Commonwealth of Australia, have invented certain new and useful Improvements in Door Checks and Closers; and I do hereby declare the following to be a full, clear, and exact description of the 10 invention, such as will enable others skilled in the art to which it appertains to make and use the same.

The invention has for its purpose to provide a door check and closer which will be 15 of simple construction; readily installed; and wherein the cost of manufacture thereof will be comparatively small.

With these and other objects in view the invention consists in the novel details of 20 construction and combinations of parts more fully hereinafter disclosed and particularly pointed out in the claims.

Referring to the accompanying drawings forming a part of this specification in which 25 like numerals designate like parts in all the views:—Figure 1 is a perspective view of the device complete in applied position; Fig. 2 is a similar view with the door open; Fig. 3 is a top plan view of the same; Fig. 4 is a 30 transverse sectional view of one of the details; and Fig. 5 is a similar view of a modified construction thereof.

Referring to the construction in detail, the device consists of an arcuate bar *m* secured 35 to a lintel *e* and a frame *d*, and to which frame the door *a* is swung in the usual manner on hinges *b*. The respective ends of the arcuate bar *m* are bent, as at *m'* and *m''*, to 40 pivotally fit within the apertured lugs *k'* formed on the supporting plate *k*.

A bracket *e* having an arm *f* is suitably fixed on the door *a*, and is provided with a boxing or casing *g* through which the arcuate bar *m* passes. A pair of cheek pieces or 45 jaws *i* and *i'* are located within the boxing *g*, and are shaped to conform with the bar *m*, and have for their purpose to frictionally engage with said bar and silence the engagement of the bracket therewith. Said pieces 50 *i* and *i'* are constructed of leather, rubber, or other similar material, and are retained within the boxing through the medium of a closure plate *h*, that is pivotally mounted on said boxing, as at *h'*. The opposite end 55 of the boxing (not shown) is constructed

with an integral wall having a suitable opening through which the bar *m* passes, as will be understood.

The degree of friction between the pieces *i* and *i'* and the bar *m* is adapted to be regulated through the medium of a plate *j*³, that is forced against the member *i* through the medium of a rod *j*, that has a threaded portion *j*² that screw threads in the downward extension of said casing *g*. A thumb nut, 60 or similar device, *j'* is provided for turning the rod *j* for adjusting the plate *j*³; and a screw *j*⁶ prevents the withdrawal of the rod *j* by engaging with the enlarged screw-threaded portion *j*². When the members *i* and *i'* are clamped lightly against the bar *m*, the swinging of the door is proportionately retarded, and if said members *i* and *i'* are clamped tightly against said bar *m* the door will be held against movement from 75 any position to which it may be set.

In the modified construction (Fig. 5) of the parts just referred to, the casing *g* has the wall thereof divided and projecting outwardly to provide lips *g*² and *g*³, and the lip *g*³ has an extended portion *g*⁴. A bolt *j*⁷ passes through the lips *g*² and *g*³, and has screw-threaded engagement with a nut *j*⁴ formed on the end of the adjusting rod *j*. The turning of the nut *j*⁴ will operate to 85 clamp the split sleeve or ring *i*² against the bar *m* to secure the door. Said sleeve is also adapted to be clamped to frictionally engage the bar for retarding the movement of the door.

A spring *q* of spiral design is mounted on the arcuate bar *m*, and is intended for serving as a buffer to the door and as a closer therefor. The spring is also adapted to be moved onto the straight portion *m'*. Said 90 spring is adapted to act under different degrees of tension by having certain portions of its length removed from action. In the present instance, the means for accomplishing this result consists of a rod *o'* swinging 95 mounted on the plate *k* at *o*², and having a hooked end *o* which engages within an aperture of the series *n*³ formed in the bar *m*. The bar *o'* is adapted to be moved to different positions through the medium of a rod *o*⁴, that engages at *o*³ with the bar *o'*, as shown in Figs. 1 and 3. With this arrangement, certain lengths or convolutions of the spring may be isolated from the remainder thereof, and since this is elective it will be 100 105 110

seen that the spring is capable of acting under variable tension. A washer or buffer piece q' is secured against the end of the spring which contacts with the plate h of the 5 bar bracket.

- The closing movement of the door may be interrupted or silenced through the medium of a chain u , which is connected to a hook x carried by the bracket casing g , and having 10 a short length u^2 that carries a pin t . Said pin t is adapted to be inserted in any one of the series of apertures n' formed in the bar m , and accordingly as said aperture is selected to one side or the other of the casing g , the 15 extent of opening or closing movement of the door a would be determined and stopped. The free end of the chain u is provided with a hook u' adapted to be engaged at any point with the spring q , and by reason of 20 which engagement the closing of the door would be made resilient when the slack of the chain u is taken up through the closing movement of said door, as will be understood. 25 The bar m is provided with rings of resilient material m^2 set at suitable intervals, and which have for their purpose to frictionally engage with the clamping piece, or pieces, in the bracket casing g of the door, and interrupt or break the opening or closing of the 30 door, as the case may be.

It is obvious that those skilled in the art may vary the details of construction and arrangement of parts without departing from 35 the spirit of my invention, and therefore I do not wish to be limited to such features except as may be required by the claims.

What I claim is:—

1. The combination with a door frame 40 and a door swinging therein of a curved arm mounted on the door frame; an adjustable spring on said arm providing a door buffer and closer; a device carried by the door adapted to engage with said spring; and a 45 radially disposed and pivotally mounted bar having a pin adapted to engage said arm and cut out variable lengths of the spring

whereby to graduate the resiliency thereof, substantially as described.

2. The combination with a door frame 50 and a door swinging therein of a curved arm mounted on the door frame; an adjustable spring on said arm; a device carried by the door and adapted to engage with said spring to provide a door buffer and closer; a flexible member carried by the door and adapted to engage with said spring at different points and provide a door check; and a device for regulating the resiliency of said spring, substantially as described. 55

3. The combination with a door frame and a door swinging therein of a curved arm mounted on the door frame; an adjustable spring on said arm; a device carried by the door and adapted to engage with said 60 spring to provide a door buffer and closer; a flexible member carried by the door and adapted to engage with said spring at different points to provide a door check; and a radially disposed and pivotally mounted 65 bar having a pin adapted to engage said arm and cut out variable lengths of the spring whereby to graduate the resiliency thereof, substantially as described. 70

4. The combination with a swinging door 75 of an arcuate bar mounted above the door, and provided with a plurality of perforations, a spiral spring mounted on said bar, a pivotally mounted rod having a hooked end adapted to engage with said apertures 80 for regulating the tension of said spring, a bracket mounted on the door and provided with an arm having a casing through which said bar passes, said casing adapted to engage with said spring, and flexible connections 85 between the bracket arm and said spring substantially as described.

In witness whereof I have hereunto set my hand in the presence of two witnesses.

DAVID JAMES HURLEY.
